OPTICAL VIEWING AND ILLUMINATING DEVICE

Albin A. Gradišar and Gustav E. Guellich, Buffalo, N. Y., assignors, by mesne assignments, to American Optical Company, Southbridge, Mass., a voluntary association

Application October 8, 1943, Serial No. 505,488

1 Claim. (CL 240—2)

1

This invention relates to new and improved means for forming the contour or profile of articles and more particularly relates to new and improved means for providing illumination during the forming operation.

An object of the invention is to provide new and improved means for forming the profile or contour of objects which makes such forming simpler and more economical.

Another object of the invention is to provide new and improved illuminating means for forming apparatus which facilitates the forming operation and allows more accurate forming of the contours.

Another object of the invention is to provide new and improved means for illuminating a tool and an area of a work piece in relative position and for viewing said work piece and tool over a considerable area whereby the relative position of said tool and work piece may be adjusted.

Other objects and advantages of the invention will be apparent from the following description taken in connection with the accompanying drawings. It will be understood that many changes may be made in the details of construction and arrangement of parts without departing from the spirit of the invention as expressed in the accompanying claim. We, therefore, do not wish to be limited to the exact details of construction and arrangement of parts shown and described as the preferred form has been given by way of illustration only.

Referring to the drawings:

Fig. 1 is a diagrammatic view, partly in section, showing the apparatus in operative position;

Fig. 2 is a sectional view taken on line 2—2 of Fig. 1 looking in the direction of the arrows and showing the tool and work in operative position;

Fig. 3 is a sectional view of the illuminating apparatus shown in Fig. 1 but on an enlarged scale;

Fig. 4 is an end view showing the grinding tool in operative position relative to a round blank; and

Fig. 5 is a view similar to Fig. 4 but showing a work blank similar to that shown in Fig. 1.

In the past, machines for forming the contour or profiles of objects have been provided with viewing means and in some cases with illuminating means.

Where the viewing means has been employed without illuminating means it was difficult if at all possible to view the tool and blank and it was not possible to obtain a well defined shadow of at least a portion of the blank and tool to allow the operator to guide the tool and work relative

2

to each other to form the desired contour or profile on the work blank. Also, where illuminating means has been employed to illuminate the work and tool, due to the character of illuminating means employed it was not possible to obtain a well defined image of the tool and blank and it was found necessary to provide a mask on the light source or between the light source and work and then to continue adjusting said mask from time to time as the forming or cutting proceeded, or else to use a different mask as the cutting or forming proceeded, and also necessary to use a different mask for each object of different contour to be formed. Such errors in the image, even though slight, still introduced errors in the size of the finished article.

It will be seen from the above that in order to obtain the proper contour or profile on the object a well defined image thereof must be obtained, which is not always possible or feasible by merely adjusting a mask or by providing new masks for the illuminating means as cutting proceeds and for each differently contoured object, such being time consuming and expensive.

It, therefore, is a principal object of this invention to provide new and improved means or apparatus for forming the contour or profile of objects wherein uniform illumination will be obtained over the entire illuminated area and a well defined image of the tool and work may be obtained at all times without the necessity of masking the light source as necessary with prior art arrangements.

Referring more particularly to the drawings wherein similar reference characters designate corresponding parts throughout the several views, the apparatus embodying the invention and adapted for carrying out the forming process is shown in Fig. 1 and consists of a viewing microscope which comprises an eyepiece 1 and an objective 2 between which is positioned the roof prism 3 for directing the image received by the objective 2 into the eyepiece and also for inverting said image.

Aligned with the objective 2 is provided the tubular member 4 containing the window 5.

In alignment with the microscope and adapted to be viewed therethrough is provided the work piece 6, on which the desired contour or profile is to be formed, and the grinding wheel or other tool 7 for forming such contour.

For illuminating an area of the work piece and the tool is provided the illuminator 8 which is shown in section in Fig. 3 on an enlarged scale.

This illuminator 8 comprises a tubular body

member 9 having the supporting flange 10 secured thereto for securing the illuminator in desired position on the machine relative to the tool, work and microscope. This flange 10 may have bolts extending therethrough for use in securing the illuminator in operative position and may also be provided with leveling screws for aligning the illuminator with the microscope as well as the work and tool.

Adjacent the upper end of the tubular body member 9 is provided the telescope objective lens system 11 which is corrected for spherical aberration, coma and color. Adjacent the opposite end of said tubular body member 9 is provided the diaphragm member 12 having the circular aperture or opening 13 over which is positioned the ground glass disc 14. This ground glass disc 14 may be either colored or clear although we prefer to make the same of a green glass to avoid fatigue in the eye sighting against the light source through the microscope and also to eliminate the effect of chromatic aberration. If such disc 14 is of green glass as stated, the light provided by the illuminator will also be substantially monochromatic. This glass disc 14 has one surface, preferably its upper surface 21 ground but not polished. Behind the disc 14 is provided the lamp socket 15 supporting the lamp 16 and also having the plug 17 for connection with a source of current to illuminate the lamp 16. The mount 18 for the lamp socket may be connected to the tubular member 9 by screws or the like 19 or could be soldered thereto as desired and the socket 15 is secured in said mount 18 by means of the set screw or the like 20. The body member 9 may be provided with slots adjacent the lamp 16, as shown, for ventilation purposes.

It is pointed out that the objective lens system 11 must be of such optical construction as to provide substantially parallel light for illuminating at least a portion of the tool and an area of the work piece.

In order to form on the work the desired profile or contour it is necessary that the work and tool be adjustably mounted relative to each other and that the microscope also be adjustably mounted to allow the scanning or viewing of a considerable area of the work piece without the necessity of stopping the forming operation to readjust the position of the work piece and tool. In order that the work and tool may be observed within a considerable range it is necessary that the clear aperture of the objective 11 be considerably in excess of the diameter of the field of the objective 2, that is, the clear aperture of the objective 11 should equal the amount of travel of the microscope and microscope objective 2. Thus the field illuminated by the illuminator 9 will be of such area that the microscope may be adjusted through a considerable range and the relative position of said tool and work may be viewed through said range without the necessity of stopping the forming operation as described above.

It is pointed out that the upper surface 21 of the glass disc 14 which is a rough ground surface, as described above, is positioned at the focal point

of the objective lens system 11. This arrangement provides more uniform illumination over the entire illuminated area and also simplifies the positioning of the lamp 16 relative to the diaphragm aperture 13 and therefore obviates the otherwise necessary accurate positioning of the lamp 16 relative to the diaphragm aperture 13.

It is also pointed out that the size of the pin hole or aperture 13 must be such as to eliminate excessive diffraction patterns and yet allow sufficient light to be provided to the objective 11 to provide illumination of sufficient intensity.

In Fig. 4 there is shown a circular work piece. The grinding wheel 22 is shown rotating on the shaft 23 and the circular work blank 24 is shown rotating on the shaft 25.

In Fig. 5 is shown an end view of a work blank of the type shown in Figs. 1 and 2 and shows the tool 26 rotated on the shaft 27 relative to the work blank 28 on which the desired contour or profile is to be formed.

It will be seen by employing the parallel light illuminating arrangement of the present application that a well defined shadow zone of the same cross section as the contour of the object will be obtained, and therefore any errors in focusing and consequent errors in size will be eliminated, and that uniform illumination and light intensity will be obtained over the entire illuminated area.

From the foregoing it will be seen that we have provided simple, efficient and economical means and process for obtaining all of the objects and advantages of the invention.

Having described our invention, we claim:

In apparatus for use with a contour forming machine an illuminator for silhouetting a portion of a forming tool on said machine and an adjacent portion of a workpiece also carried thereby and adapted to be profiled by said forming tool, said illuminator comprising an elongated tubular housing, a telescope objective lens system carried adjacent and completely enclosing an end of said tubular housing, said lens system being corrected for spherical aberration and coma, a fixed partition disposed transversely within said housing intermediate the ends thereof and arranged to divide the interior of the housing into separated front and rear compartments, an aperture of relatively small diameter as compared to the diameter of the said lens system formed in said partition in axial alignment with said lens system, said aperture being located at the rear focal point of said lens system, a monochromatic filter within said rear compartment and positioned to overlie said aperture, means for securing said filter in such position, a diffusing surface formed on the forward face of said filter and positioned closely adjacent said aperture, and a lamp within said rear compartment and located closely adjacent said filter, whereby a beam of parallel light of a single color may be projected by said illuminator when employed for silhouetting said forming tool and workpiece.
